UNITED STATES PATENT OFFICE.

COLIN F. MACKENZIE AND ROBERT J. PENSE, OF SHELL, WYOMING.

RURAL MAIL-BOX.

SPECIFICATION forming part of Letters Patent No. 731,061, dated June 16, 1903.

Application filed January 16, 1903. Serial No. 139,268. (No model.)

To all whom it may concern:

Be it known that we, COLIN F. MACKENZIE and ROBERT J. PENSE, citizens of the United States, residing at Shell, in the county of Big-horn and State of Wyoming, have invented certain new and useful Improvements in Rural Mail-Boxes, of which the following is a specification.

Our invention relates to rural-delivery mail-boxes, and has for its object the provision of a counterbalanced box pivoted to the side of a fence-post or other convenient place in position, so that the carrier may pull the box out near his wagon-seat and deposit or extract mail without getting out of his wagon.

A further object is the provision of a self closing and opening lid for said box.

We attain these objects by the construction illustrated in the accompanying drawings, in which—

Figure 1 is a rear elevation showing the box in normal position pivoted upon the side of a post. A portion of the box is shown cut away to illustrate the manner of fastening the box to the pivotal bracket-casting and counterbalancing-arm. Fig. 2 is a side elevation of the same, showing in dotted lines the position of the box when pulled down or turned on its pivot to permit the extraction or deposit of the mail and also showing the weighted counterbalancing-arm for opening and closing the lid.

The mail-box 1 is preferably rectangular in cross-section and made of sheet metal. It is provided with a slanting lid or cover 2, which is hinged at 3 to the rear top edge of the box. A rod 4, which serves as the pin of the hinge 3, is bent at one end (shown in dotted lines in Fig. 1) and soldered or otherwise fixed to the under side of the lid. At its other end it is bent to hang down along the side of the box just a little forward of the hinge and is provided with a counterbalancing-weight 18. This weighted counterbalancing-arm 4 tends to keep the lid closed when the box is standing in its normal position, and when the box swings outward and down, as will be presently explained, the weight 18 will turn the arm 4 and lift or open the lid. The box is fastened at its lower end upon a bracket-casting 5, having a flat vertical bracket-arm 6 and the horizontal bracket-arm 7 fixed, re-

spectively, to one side and the bottom of the box by the bolts or rivets 8. At the junction of the vertical and horizontal bracket-arms of the casting is the pivot-hub 9, having the central bore 10, which forms the pivotal bearing of the swinging box. Depending from the hub of said bracket-casting 5 and in line with the vertical bracket-arm 6 thereof is a long counterbalancing-arm 11, provided at its end with a weight 12. The box is pivotally fastened to the side of a post 13 by means of a headed pivot-bolt 14, which passes through the central bearing 10 of the hub 9 and through a hole in the post. This pivot-bolt is shouldered or enlarged for a distance from its headed end where it passes through the hub, and between this shoulder and the post we place a washer 15, so that when the pivot-bolt is tightened up in the post the binding will come on the washer and not on the hub, and hence the bracket-hub will be free to turn or swing on the enlarged shoulder-bearing end of the pivot-bolt. A hand cord or chain 16, which is fastened in the eye 17 near the top of the front of the box, hangs out in reach of the carrier. The post on which the box is pivoted is preferably planted at the side of the road out of the way of passing vehicles, and by having the box pivoted thereon so that it can be pulled down and out to the position shown in dotted lines in Fig. 2 enables the carrier to deposit or extract the mail without leaving his wagon and without driving very close to the post. The advantage of having the box pivoted to swing down and out away from the post is also seen in case, as is usual, that there is a ditch at the side of the road. In such case the post may be planted on the far edge of said ditch, and the carrier need not drive down into the ditch, but can reach out and catch the hand-cords and pull the box down and out near his seat.

The rural carrier, who usually travels in a wagon or on horseback, drives up in front of the box and reaches out and grasps the hand-cord 16 and pulls the box down and out near his seat, where it is convenient for him to extract or deposit the mail and hold it in this position. If desired, the carrier may pull the box down lower than as shown in dotted lines in Fig. 2 and dump its contents into his wagon. When the box is pulled down, the weight 18

on the end of the counterbalancing-arm 4 on the lid will cause said arm to turn on its hinge 3, and as the arm is rigidly fixed to the lid it will also cause the lid to turn on the hinge, and thereby open the box. As soon as the carrier has extracted or deposited the mail he releases his hold on the hand-cord, and the box will turn up and back to its normal position by the force of the weight 12 on the counterbalancing-arm 11. At the same time the box is turning back the weighted counterbalancing-arm 4 will turn back on its hinge and close the lid of the box against the rain, &c.

While we have described our invention as 15 constructed for use as a rural mail-box, it may be used for any purpose for which it is adapted and may be modified in details of structure and arrangement to adapt it for its various purposes without departing from 20 the spirit and scope of the concluding claims.

We claim—

1. A rural mail-box comprising a swinging box pivoted at its lower end to a side support and having a weighted counterbalancing-arm 25 depending diametrically from its bottom substantially in line with the length of the box, substantially as described.
2. In a rural mail-box, the combination with

a supporting-post, of a swinging box pivoted at its lower end to the side of the post, a 30 weighted counterbalancing-arm diametrically depending from its bottom substantially in line with the length of the box, a lid on its top hinged axially parallel with the box-pivot, and a weighted counterbalancing-arm rigidly 35 secured to the lid at its hinged edge and swinging and depending therefrom alongside of the box, substantially as described.

3. The combination with a bottomly-pivoted swinging box, of a counterbalancing-arm 40 depending therefrom substantially in line with the length of said box, a lid hinged thereto at its rear top edge axially parallel with its pivot and a weighted counterbalancing-arm rigidly secured to and depending 45 from the hinge edge of said lid and swinging axially parallel with the box-pivot along the side of the box, substantially as described.

In testimony whereof we affix our signatures in presence of two witnesses.

COLIN F. MACKENZIE.
ROBERT J. PENSE.
